UNITED STATES PATENT OFFICE

2,498,215

ROLLED PAPER DISPENSER

Burton H. Locke, Framingham, Mass.

Application July 26, 1947, Serial No. 763,805

4 Claims. (Cl. 242—55.5)

1

My invention relates to improvements in dispensers for rolled paper and is primarily adapted to rolled toilet paper. The object of the invention is to provide a dispenser that permits easy and quick loading of the roll of paper and affords a means whereby the paper can be sheared from the roll at will, thereby, eliminating the usual necessity of perforating the paper into sheets as is common practice in the art. Other objects are to afford a dispenser that totally encloses the roll of paper and will thereby afford sanitary protection thereof; and a dispenser that can be produced cheaply for reason that the housing and also the cover is susceptible of complete moulding from plastic, or the like. A further object is to afford an improvement in the dispenser set forth in my application filed March 14, 1947, Serial No. 734,706, now abandoned, by the addition of an improved cover to reenforce the construction of the dispenser and to afford complete enclosure of the roll of paper.

In the accompanying drawing:

Figure 1 is a front elevation of my improved dispenser with the cover shown in place.

Figure 2 is an end elevation of same taken at the loading end.

Figure 3 is a bottom view of the dispenser with the cover removed and when arranged to support the roll of paper axially on a spindle.

Figure 4 is an enlarged fragmental section taken on line 4—4 of Figures 1 and 2, to show the reenforced clip construction.

My improved dispenser comprises generally a cylindrically shaped housing 10 conforming to the general shape and size of the full roll of paper to be dispensed. In the construction shown by Figures 1 and 2, the roll of paper is supported at its periphery by the housing and this appears to be the simplest method of supporting the paper. However, the roll of paper could be supported on a spindle which could be provided integral with the closed end of the housing, as shown in Figure 3. One end 11, of housing 10, is open to permit quick and easy insertion of the roll of paper and the other end 12 is generally closed to strengthen the construction and to insure that the roll of paper be properly confined within the housing 10.

The back side portion 13, of housing 10, is generally provided with a flat portion 14 which generally extends endwise beyond the housing and has a plurality of holes 15 to receive screws, or nails, or the like, for attaching the dispenser in operating position against a wall or other support. A slot 16 for dispensing the paper is provided

through housing 10 and extends from the inside face 17, of the closed end 12, to the open end 11 thereof. The open end 18, of slot 16, diverges to facilitate the insertion of the loose end of the paper therein, as the roll of paper is slid into the dispenser housing. The roll of paper can be quickly and easily slid into the open end 11, of housing 10, and the side of the free end of the paper slid into slot 16 simultaneously therewith.

Therefore the dispenser is susceptible of quick and easy loading.

A shearing blade 19 that extends outward from housing 10 is provided on one side of slot 16 and the outer edge 20, thereof, is sharp and it could be serrated as shown in Figure 1 if desirable for better shearing of the paper. The paper is sheared from the roll by a crisp tug at the loose end "A," of the roll of paper "B," executed diagonally with the shearing edge 20. As shown, the shearing blade 19 extends a distance outward from the housing 10 so that the free end of the paper will be left protruding outside the dispenser, after the paper is sheared on the edge 20, for the user to grasp the next time.

I conceive another construction wherein a spindle 21, as shown in Figure 3, could be provided to support the roll of paper axially. In this instance, one end 22, of spindle 21, would be integral with the closed end 12, of housing 10, and the other end 23 would be free and is usually chamfered to permit the roll of paper being readily slid onto the spindle as it is slid into the open end 11, of housing 10.

The housing 10 is weakened at the open end 11, thereof, by the slot 16 extending through same. In order to strengthen the construction at this end, I conceive the addition of a slip-on cover 24 that will function to interlock with the wall of the housing, thereby retaining same rigidly intact. The cover 24 comprises, in this instance, a circular plate 25 conforming to the outside of the housing and arranged to abut the end 26 thereof. There is a sleeve section 27, integral with plate 25, to fit the inside of the housing wall and a plurality of clips 28 to fit over the outside of same to cooperate in rigidly retaining the housing wall therebetween. A triangular shaped rib 29 is provided between each clip 28 and sleeve 27 for the purpose of rigidly connecting the said clips to the sleeve. A plurality of slots 30 are provided in the end of housing 10 to receive the ribs 29 and to eliminate interference therewith. The outer edge of plate 25 is cut away at 31 to clear the flat base portion of the housing 10. It is obvious that cover 24 could be easily and

quickly slid into place after the roll of paper is slid into the housing. The cover 24 also serves to complete the enclosure of the roll of paper, thereby completing the sanitary protection thereof.

It is obvious that the construction of the housing is such that it can be injection moulded in one piece which would afford a relatively inexpensive article to produce. Also, the cover can be moulded in one piece and, therefore, the complete dispenser is susceptible of being produced cheaply and at a low cost to the consumer.

I do not wish to be confined to the exact details set forth as same are susceptible to modification without departing from the spirit or scope of the invention to be set forth in the claims to follow. For example, the plurality of clips 28 could be extended to form a continuous band, or sleeve, to encircle the housing without departing from the reinforcement of the open end of the housing. Conversely, the sleeve 27 could be replaced by a plurality of clips if desirable.

I claim:

1. A dispenser for rolled paper comprising a housing to receive a roll of paper, one end of said housing being open to admit the roll of paper, one side of said housing being adapted for mounting in an operating position, a longitudinal slot in said housing for dispensing the paper, said slot being open cooperatively with the open end of said housing to facilitate insertion of the paper, a shearing blade protruding from said housing at one side of said slot, the outer edge of said blade being suitable to sever the paper thereon, and a slip-cover for the open end of said housing comprising a plate to abut the end of the housing wall and thereby complete the enclosure of the roll of paper, and a sleeve portion to fit inside of the housing wall, and a plurality of intermittently spaced clips to contact the outside of the housing wall to secure the said wall against said sleeve and thereby retain the open end of the housing in operating position.

2. A dispenser for rolled paper as described in claim 1, with reinforcing ribs intermediate the said sleeve portion and said clips of said cover.

and slots in the open end of the housing wall to admit said ribs as the cover is applied to the housing.

3. A dispenser for rolled paper comprising a housing to receive a roll of paper, one end of said housing being open to admit the roll of paper, one side of said housing being adapted for mounting in an operating position, a longitudinal slot in said housing for dispensing the paper, said slot being open cooperatively with the open end of said housing to facilitate insertion of the paper, a shearing blade protruding from said housing at one side of said slot, the outer edge of said blade being suitable to sever the paper thereon, and a slip-cover for the open end of said housing comprising a plate to abut the end of the housing wall and thereby complete the enclosure of the roll of paper, means projecting from said plate to contact the inside of the housing wall and means projecting from said plate to contact the outside of the housing wall to secure the said wall therebetween and thereby rigidly retain the open end of the housing in operating position.

4. A dispenser for rolled paper as described in claim 3, with reinforcing ribs intermediate the housing wall contacting means of said cover, and slots in the open end of the housing wall to admit said ribs as the cover is applied to the housing.
